UNITED STATES PATENT OFFICE.

GEORGE KOCH, OF CASS, PENNSYLVANIA.

IMPROVEMENT IN DRILLING-MACHINES.

Specification forming part of Letters Patent No. 118,950, dated September 12, 1871.

To all whom it may concern:

Be it known that I, GEORGE KOCH, of Cass, in the county of Venango and State of Pennsylvania, have invented a new and valuable Improvement in Drilling-Machines; and I do hereby declare that the following is a full, clear, and exact description of the construction and operation of the same, reference being had to the annexed drawing making a part of this specification, and to the letters and figures of reference marked thereon.

Figure 1 of the drawing is a representation of a side elevation of my invention. Fig. 2 is a similar view of opposite side of the same.

This invention has relation to the improvement of machines for drilling oil and other wells; and consists in the application to the band-wheel of a pair of ratchet-wheels, with suitable spring-pawls located on the band-wheel, the object in view being to allow the drill to fall and strike from the force of gravity alone, thereby securing a harder blow than is obtained where the drill is made to drop by the aid of a stiff crank—the ordinary process of drilling.

In the accompanying drawing, illustrating this invention, A represents a band-wheel loosely hung on the transverse shaft B, which is supported by standards C. D is the beam, oscillating on the top of the post D', supporting a drill, E, which is hung to its forward end, and connected with the shaft B by connecting-rod E' and

crank E''. F F designate ratchet-wheels, which are keyed to the shaft B on opposite sides of the band-wheel. G G represents pawl, and G' G' springs secured to the faces of the band-wheel. H shows orifices through the ratchet and band-wheels.

This machine operates as follows: As the band-wheel revolves toward the drill end of the machine the pawls engage with the ratchet-wheels and rotate the shaft until the drill is raised to its highest point, whereupon it falls of its own gravity, and independently of the revolution of the band-wheel. A stiff crank motion may be substituted for the one described by inserting a pin through the orifices H, thereby establishing a connection to operate the drill in both directions.

This invention is especially applicable to the drilling of artesian wells with cable tools.

Having described my invention, I claim—

In a drilling machine, the combination, with the walking-beam D and its connecting ropes or rods, of the loose pulley A, provided with pawls G G, the shaft B, with its perforated ratchet-wheels F F, and crank E'', all constructed and operating substantially as specified.

In testimony that I claim the above I have hereunto subscribed my name in the presence of two witnesses.

Witnesses:

GEORGE KOCH.

J. W. SMULLIN,
S. C. RUMBERGER.
